(57) **CLAIM**

We claim the ornamental design for a oval stone, as shown and described.

DESCRIPTION

FIG. 1 is a top, front, and right side perspective view of an oval stone;

FIG. 2 is a bottom, front, and left side perspective view thereof;

FIG. 3 is a top view thereof;

FIG. 4 is a bottom view thereof; and

FIG. 5 is a left side view thereof, the right side view being a mirror image thereof; and,

FIG. 6 is a front side view thereof, the rear side view being a mirror image thereof.

The broken lines in FIGS. 1, 2, 4, 5, and 6 depict portions of the oval stone that form no part of the claimed design.
